UNITED STATES PATENT OFFICE.

PETROS C. OTTINGER, OF ATLANTA, GEORGIA.

CUFF-HOLDER.

No. 913,761.

Specification of Letters Patent.

Patented March 2, 1902.

Application filed July 15, 1901. Serial No. 443,719.

To all whom it may concern:

Be it known that I, PETROS C. OTTINGER, a citizen of the United States, residing at Atlanta, in the county of Fulton and State 5 of Georgia, have invented certain new and useful Improvements in Cuff-Holders, of which the following is a specification, reference being had to the accompanying drawings.

16 This invention relates to improvements in cuff holders or devices for fastening detachable cuffs to the shirt sleeves.

15 The object of the invention is to provide a simple and practical device of this character especially adapted for use in connection with link or cross bar cuff buttons and to provide one which may be easily attached to and removed from the cuff and which will effectively hold the latter in an adjusted 20 position upon the shirt sleeve.

25 With the above and other objects in view, the invention consists of the novel features of construction and the combination and arrangement of parts hereinafter fully described and claimed, and illustrated in the accompanying drawings, in which—

30 Figure 1 is a view showing the application of the invention to a cuff; Fig. 2 is a perspective view of the holder; and Figs. 3 and 4 are detail longitudinal and transverse 35 sectional views through the spring clasp.

35 In the drawings 1 denotes a cuff having button holes 2 adjacent to its corners; 3 denotes an ordinary link or cross bar cuff button, and 4 denotes the improved cuff holder.

40 The holder consists of a body bar 5 having a sleeve engaging clasp 6 at one end and a cuff engaging means at its opposite end. Said cuff engaging means consists of a cross bar 7 rigidly secured at its center to one end of the body bar 5 at right angles to the same and it is curved longitudinally and provided at its two ends with spherical heads 8. The latter are adapted to be inserted in button holes 2 at the inner end of the cuff, as clearly shown in Fig. 1 and tends to unite 45 said inner ends or corners while the outer ends or corners are united by the cuff button 3.

50 The clasp 6 consists of two pivoted jaw

members 9, 10 each of which is constructed from a single piece of metal plate and has at one end a finger piece 11 and at points intermediate its ends apertured bearing ears 12 which are bent up from the opposite sides 55 of the metal plate. The opposite ends of the members 9, 10 are provided with co-acting jaws 13, 14 of semi-circular form. Said jaws are flat and have inwardly projecting flanges 15 which telescope each other, the 60 jaw 14 being of slightly less diameter than the jaw 13, as clearly shown in the drawings. The spaced bearing ears 12 of the two members have their apertures in register to receive a pivot 16 formed by reducing one end 65 of the body bar 5 to provide an annular stop shoulder 17. Said members are retained upon the pivot 16 by upsetting the outer end of the latter, as shown at 18. A coil spring 19 surrounds the pivot between the bearing 70 ears 12 and has its two ends 20 bearing against the inner faces of the finger pieces 11 so as to force the latter apart and the jaws 13, 14 together.

75 By constructing the jaws of the clasp as set forth, it will be seen that they will effectively engage the shirt sleeve without permitting the clasp to slide upon the same and without danger of tearing the sleeve.

Having thus described the invention what is claimed is:

The herein described cuff holder comprising a straight body bar 5 formed at one end with the reduced cylindrical portion 16 to provide the stop shoulder 17, a cuff engaging 85 means at the other end of the body bar, a spring jaw clasp consisting of two jaw members, each provided at one end with a finger piece and at its other end with a jaw, the intermediate portions of said members being 90 bent to form spaced apertured pivot ears to receive the reduced cylindrical portion 16 of the body bar, the ears of one member being adapted to enter between the ears of the other and one of the ears of the last mentioned member being adapted to engage said shoulder 17, said members being retained upon the portions 16 of the body bar by upsetting or heading the end 18 of said portion 16, the jaws of said members being of flat 100

circular shape and having their outer edges formed with continuous inwardly projecting flanges, the flange on one jaw being adapted to enter the flange upon the other, and a coil spring arranged upon the reduced portion 5 of the body bar between the pivot ears of the jaw members and having its free ends bearing against the inner or opposing faces

of the finger pieces of the members to force their jaws toward each other.

In testimony whereof I hereunto affix my signature in the presence of two witnesses.

PETROS C. OTTINGER.
